UNITED STATES PATENT OFFICE.

FRANCIS E. DRAKE, OF DAVENPORT, IOWA.

AUTO HOIST.

1,413,526.

Specification of Letters Patent. Patented Apr. 18, 1922.

Application filed October 27, 1920. Serial No. 419,841.

To all whom it may concern:

Be it known that I, FRANCIS E. DRAKE, a citizen of the United States, residing at Davenport, in the county of Scott and State 5 of Iowa, have invented certain new and useful Improvements in Auto Hoists, of which the following is a specification:

The invention has reference to machines or apparatuses for lifting or hoisting heavy 10 objects and has for its principal object to provide a device of this character having improved features serving to enlarge the range of usefulness to which the device may be applied and providing a structure in 15 which lightness of construction is combined with increased stability and ease of operation, with adjustability of the lifting element to decrease or enlarge the leverage.

An additional object is to provide a hoisting apparatus of generally improved construction, in which the lifting elements are adjustable either vertically or longitudinally so as to adapt the device to various purposes and to insure the load being carried centrally 25 with respect to the hoist frame at all times.

An additional object is to provide hoisting apparatus of a mobile character and to provide it with improved steering means, enabling the hoist to be guided in any direction 30 in the course of transferring a load to a particular location.

With the above and other objects in view, the invention may be said to reside generally in the details of construction, combination 35 and arrangement of parts, as will be herein-after more fully pointed out and described, reference being had to the accompanying drawings, wherein—

Figure 1 is a side elevation of a hoist constructed in accordance with the invention.

Figure 2 is a front elevation.

Figure 3 is a top plan view.

Figure 4 is a detail, sectional view taken on line 4—4 of Figure 1, and

Figure 5 is a detail view of the upper joint connection between the pivoted ends of the lift-arm.

In the preferred embodiment of the invention, the main frame and lifting arms are 50 constructed of suitably sized commercial steel bars, riveted together and held apart by short pipes or separators through which the rivets pass, as indicated more clearly in the several views of the drawing. The uprights 55 are of channel iron or steel and mounted upon

the frame at the back and sides thereof. The entire frame work is of a skeleton structure so as not to add unnecessarily to the weight of the device and comprises, a base 1, formed U-shaped, and having its outer ends connected by a cross-axle 2, upon which are mounted wheels or castors 3. A second shaft 4, is arranged inwardly toward the arched end of the base and is likewise provided with castors 3. Two of the three uprights carried by the frame are mounted upon the latter inwardly of axles 2 and 4, and near the latter as shown to advantage in Figure 1. These uprights, indicated at 5 and 5' respectively, extend upwardly to an appreciable height and have their channeled or grooved surfaces facing inwardly to provide slideways within which work slide rollers 6. The rollers are carried by axles 7, rigidly connected to a lifting bar 8 and to 75 which they are angularly disposed as shown in Figure 2. The lifting bar extends cross-wise in a horizontal plane between the side uprights and is disposed to move vertically between the uprights, the guide rollers keeping it in position while being adjusted. Connecting the side uprights at their upper ends is a bridge bar 9, which supports the bearing units 10, said units being fastened to the bar by suitable means 11. Supported 80 through these bearings is a worm-gear shaft 12, provided adjacent each end with a cable drum 13. The gear 14 of this shaft is located at a central point, and enclosed within the gear case 15, which likewise encloses the worm 16. The worm shaft extends rearwardly at right angles to the worm gear shaft and is journaled through a boxing 18 suitably mounted at the upper terminal of rear upright 19. This upright is located at the 85 rear of the base and at a point centrally disposed with respect to the side upright, and is likewise arranged with its channeled or grooved face opening inwardly and provides a vertically disposed slideway for a guide element 20. This element consists of a top plate 21, having several bolts 22, depending downwardly therethrough and engaging a lower or clamping plate 23, held in place by nuts 24. The top plate is provided with arms 25, which extend outwardly and embrace the rear uprights on opposite sides, being connected across the rear wall of the uprights by means of a guide roller 25'. This roller travels on the outside of the upright and takes 100

105

110

care of the forward and backward motion of the lifting element during the operation of the hoist.

The lifting element comprises a pair of 5 lifting arms 26, each having its inner end clamped between bars 21 and 23, and pivoted upon respective connecting bolt 22, which passes therethrough. The arms are so disposed between the uprights as to extend over and across the lifting bar 8, which thus provides a support or fulcrum for the arms. At its outermost end each arm is provided with a hook 27, and by reason of the pivotal connection, the outer ends of the 10 hook may be adjusted horizontally across the fulcrum 8 so as to approach or recede from each other. As the arms swing in the arc of a circle it is evident that the adjustment in a horizontal plane across the fulcrum tends 15 to increase the leverage as the arms approach and to decrease it as they separate. In order that the arms may move in unison whenever one of them is actuated they are connected adjacent their pivoted terminals, by a 20 knuckle-joint coupling 28, consisting of ball and socket knuckle to automatically keep the arms equi-distant from a line passing horizontally through the center of the frame and lifting bar. Accordingly, the adjustment of 25 one of the lifting arms in a horizontal plane, causes the corresponding adjustment of the co-operating arm, and thus allows arms to be conveniently and promptly adjusted to suitably engage and support the object to be 30 hoisted.

The weight or object to be hoisted is supported upon that portion of each arm which projects forwardly beyond the fulcrum or bar 8, upon which it rests, and to avoid over-balancing of the arms when heavy objects 35 are being lifted, an equalizing device is associated with the inner or pivoted terminals of the arms. It comprises an equalizing cable 29, having its terminals connected to eye-bolts 30 and 22 carried respectively by the fulcrum bar 8, and guide 20, to which they are adjustably secured by means of tightening nut 31. This cable is passed over sheave-wheels 32 which govern the direction of the 40 equalizing cable. One of these sheaves is mounted at the rear end of the base, and below the lifting-arm, while the other two are respectively mounted adjacent the upper ends of the uprights, one being suitably 45 bracketed to the upper edge of cross bar 9, while the other is carried by braces 33, which support and connect the uprights to which they are fixedly attached. This equalizing arrangement tends to keep the lifting arms in 50 a horizontal position at any and all times holding it balanced upon the fulcrum bar, at all stages in its vertical adjustment.

The raising or lowering of the lifting arms is accomplished through movement of fulcrum bar 8 which is supported in position 55

between the side uprights by means of hoisting cables 34, wound about the cable drum 13 and having their ends secured to adjustable eye bolts 35, carried by the fulcrum bar. As the drums wind the cable the fulcrum bar is raised vertically between the uprights carrying with it the lifting arm, and the object supported thereby. Slide rollers 6, tend to hold the lifting bar firm in its hoisting movement while the rear guide 20 prevents any backward or forward motion. By the fulcrum bar, the operator is enabled to locate the lifting arm at any desired height without interfering with the travel of the cable and the guide element keeps the moving part centrally disposed with respect to the same. Adjustment of either the equalizing or hoisting cables is possible through the eyebolt and tightening nut arrangement, since adjustment of these parts will tend to tension 75 or relax the cable to the desired degree.

The cable drums are rotated to wind or unwind the hoist cables through the rotation of worm-shaft 17. The shaft is provided adjacent one end with a chain sheave 36, about 80 which is looped the operating chain 36'. Upon the pulling of the chain the sheave is turned to rotate the worm shaft, causing the worm 16 to rotate gear 14 for turning the cable drum, and winding or unwinding the 90 hoist cables according to the direction in which the chain is pulled. The worm and worm-gear mechanism is preferred not only on account of its simplicity and safety, but particularly on account of its ability to stay 95 put regardless of load or position.

To increase the mobility of the hoist and to enable it to be readily transported from place to place, a steering dolly, in the nature of a jack is associated with the forward or arched end of the base and comprises a casting 37, riveted or otherwise fixed to the frame, and provided with a ball socket 38 to receive the ball end 39 of the angularly disposed end of the dolly handle or lever 40. This lever is mounted upon rollers 41 and has its two divergent portions suitably braced as at 42. In the normal or ordinary position of the parts, the dolly is disposed with the rollers faced outwardly from the frame and provides an auxiliary support for the rear end. The ball 39, however, turns easily within the socket 38, so that upon forcing the handle down the rear end of the frame is lifted clear of the supporting structure, and the weight of the same supported upon rollers 41. The ball and socket joint allows the dolly to be readily turned to either side, which enables the hoist to be guided in any direction in the course of transferring the 105 load to any selected location.

In using the hoist, the hook ends of the lifting arms are employed for supporting the weight or object to be hoisted and may be either swung together, so as to be used as a 110

single hook, for lifting out motors, transmission, et cetera, or they can be placed any distance apart throughout the width of the frame for engaging objects of a greater bulk. The hooks also serve as supports, permitting a bar or such to be disposed transversely thereacross when it is desired to raise an auto by the frame or springs to enable a mechanic to disassemble the front 10 axle complete. The mobility of the hoist enables it to be readily applied to the rear end of an auto to permit the same operation. As the lifting bars are moved vertically through a corresponding adjustment of the 15 fulcrum bar 8, upon which it rests, the weight or object supported thereby is likewise elevated; the arms being balanced by the action of the equalizer. It is evident that a hoist of the character above described 20 is not confined to auto work only, but is capable of a wide range of usefulness and in desirable instances may be used as a working platform in repairing line shafting, electric wiring, elevating heavy merchandise, et 25 cetera.

The foregoing description and accompanying drawings have reference to what might be considered the approved or preferred form of my invention. I desire it to 30 be understood that I may make such changes in the construction, combination and arrangement of parts, materials, dimensions, et cetera, as may prove expedient and fall within the scope of the appended claims.

Having thus described my invention, what I claim as new and desire to secure by Letters Patent is:

1. A hoist comprising a frame having a movable guide, lift-means fulcrumed on said 40 guide and horizontally adjustable, and means for moving the guide to adjust the lift-means vertically.

2. A hoist comprising a frame having a movable guide, lift means fulcrumed on said 45 guide and horizontally adjustable, means for moving the guide to adjust the lift means vertically and means for holding the lift means balanced on the fulcrum at all points in the adjustment of the latter.

3. A hoist comprising a frame having a movable guide, weight-carrying means adjustable in the frame and pivoted at one end to the guide, and an adjustable fulcrum for the weight-carrying means, along which the 55 latter can be horizontally adjusted to vary the leverage, and means for raising the fulcrum to lift the weight-carrying means.

4. A hoist comprising lift-arms, pivotally fixed at corresponding ends, with their respective outer or weight-lifting ends horizontally adjustable towards or away from each other, means for adjusting the lift-arms vertically, and means for causing the arms to move in unison when horizontally adjusted. 60

5. A hoist comprising lift-arms, pivotally fixed at corresponding ends, with their outer or weight-supporting ends movable in a horizontal plane, a member vertically movable beneath the weight supporting ends of the lift-arms and providing a fulcrum support therefor, a knuckle-joint connection at the pivoted ends of the arms for keeping them equi-distant from a central point in the fulcrum at all times in their horizontal adjustment, and means for adjusting the fulcrum and lift-arms vertically in lowering or raising a load. 70

6. A hoist comprising lift-arms, pivotally fixed at corresponding ends with their respective outer or weight supporting ends movable in a horizontal plane, a vertically adjustable member below the lift-arms, and providing a fulcrum support therefor, a knuckle-joint connection at the pivoted ends 80 of the arms for keeping them equi-distant from a central point in the fulcrum at all times in their horizontal adjustment, means for adjusting the fulcrum vertically to raise or lower the lift-arms, and means for holding the arms in horizontal position at any 85 and all times. 90

7. A hoist, comprising three uprights relatively disposed to form a triangle, a lift-member disposed cross-wise between two of the uprights and movable in a vertical direction therebetween, an auxiliary member cooperating with the third upright and similarly adjustable, a weight supporting arm, disposed inwardly of the third upright, with one terminal pivoted to the auxiliary member and the outer or weight supporting terminal disposed forwardly of the lift-member, upon which it rests, and means for simultaneously moving the auxiliary and lift-members whereby the opposite ends of the weight-supporting arm are uniformly adjusted in the raising or lowering of a load. 95 100 105

In testimony whereof I affix my signature in presence of two witnesses.

FRANCIS E. DRAKE.
